(57) **CLAIM**

The ornamental design for a clock face, as shown and described.

DESCRIPTION

FIG. 1 is a front plan view of a first embodiment of a clock face, showing our new design; and,

FIG. 2 is a front plan view of a second embodiment of a clock face, showing our new design.

The gray-shaded portions of the clock face represent a contrast in appearance.

1 Claim, 2 Drawing Sheets

FIG. 1

FIG. 2
